UNITED STATES PATENT OFFICE.

GEORGE A. KARG, OF BROOKLYN, NEW YORK.

STREET CAR AND STATION INDICATOR.

Application filed November 6, 1924. Serial No. 748,006.

To all whom it may concern:

Be it known that I, GEORGE A. KARG, a citizen of the United States, residing at Brooklyn, in the county of Queens and State of New York, have invented certain new and useful Improvements in Street Car and Station Indicators, of which the following is a specification.

This invention relates to a novel street and station indicator for cars, particularly street railway cars, subway cars and the cars of elevated railroads or the like, and it is the principal object of the invention to provide such an indicator permitting of a simple operation and enabling passengers to ascertain at a glance, the name of the station or street at which the next stop will be made.

My experience has shown that it is at present very difficult, especially when the cars of a train are crowded, or only one conductor is employed to attend a number of cars to obtain quickly information desired concerning the next stop to be made.

My invention effectively does away with these disadvantages and permits every passenger to ascertain at a glance the name of a street or station which the car or train approaches.

Another object of the invention is the provision of means for operating the indicator on a moving train or car without interference with the traffic and without interference with the proper operation by authorized persons.

Another object of the invention is the provision of a street and railway car indicator allowing the automatic coupling and uncoupling of the cars of a train without the necessary special attention attendant thereto.

A still further object of the invention is the provision of an indicator of this type, the indicating features of which are visible from all points of a car and are enclosed within a protective cover.

It is also one of the objects of my invention to select the location of the indicator operating means to suit the particular make of cars used and the particular make up of a train, so that in one type of cars the operating means for the indicator are located on the platforms, while with another type they may be located at the ceiling of the car or at any desired and suitable places too numerous to be specifically mentioned.

These and other objects of my invention and advantages produced thereby will become more specifically known as the specification thereof or description proceeds, and will then specifically be pointed out in the appended claims.

In the accompanying drawings, forming a material part of this disclosure:—

Figure 1 is a side elevation of a railway car equipped with an indicator constructed according to the present invention, the type of car is the one at present in use in the municipal subways of the city of New York.

Figure 2 is a view similar to Figure 1 showing the indicator constructed according to the present invention on a car preferably used by the Interborough Railway in the subways of New York.

Figure 3 is a front elevation of a street and station indicator constructed according to the invention, partly in section, on line 3—3 of Figure 1.

Figure 4 is a section on line 4—4 of Figure 3.

Figure 5 is a top plan view of an operating handle.

Figure 6 shows in section the lower ends of two adjoining cars of a train, partly in section and illustrates the manner of coupling the indicating devices on several cars if they are to be operated from a single point.

Figure 7 illustrates a modified form of the device automatically operated from a stationary finger secured to the station platform, partly in section.

Figure 8 is a section on line 8—8 of Figure 7.

In the type of cars illustrated in Figure 1, and generally indicated by the numeral 10, having two sliding central doors 11 and 12, the indicating device, the casing of which is generally indicated by the numeral 13, is supported by a frame cheaply made of piping or the like and having vertical posts 14, 15 connected on top by a cross-tube 16. One frame is erected on either side of the car, and the posts 14 and 15 are cross-connected on top by tubular cross rods or pieces of pipe 17 and 18. The lower ends of the pairs of posts 14 and 15 are supported by the floor 19 of the car.

As shown in Figure 3, vertical operating rods 20 are provided within the posts 14, and as the construction on both sides are

identical, it will be sufficient to describe one for the understanding of both, they can be operated from either end.

The rods 20 extend with their lower ends 5 through the floor 19 of the car 10 and rotate in suitable bearings of a bracket 21 secured to the underside of a car bottom 19, and carry at their lower ends bevel gears 22 in mesh with suitable bevel gears 23 on horizontal shafts 24. Posts 20 carry also, at their extreme lower ends, bevel gears 25 in mesh with bevel gears 26 of shafts 27 disposed at a right angle to shafts 24. Shafts 27 are journalled in suitable bearings of brackets 21 and carry, at their opposite ends, bevel gears 28 in mesh with bevel gears 29 at the lower ends of vertical shafts 30 guided in suitable guide sleeves on brackets 21, and encased in pipe lengths 31 closed at the 10 top by caps 32 through which the upper ends of shafts 30 extend and receive removable operating handles 33 of a construction clearly illustrated in Fig. 5. As there shown, the rounded outer ends of the handles 33 carry indicating fingers 34 and marks 35 on the caps 34 indicate the proper position of the handles when attachment is made to the posts 30.

Within the casing 13, as illustrated in 30 Figure 4, an upper roller 36 and a lower roller 37 are rotatably arranged to rest with their ends in the end walls of the casing, and a web of fabric 38 is unwinding from one of the rollers and simultaneously winding it- 35 self upon the other in the well known manner, or vice versa. The shaft of roller 36 carries a gear 39 in mesh with a smaller gear 40 on a stub shaft 41, and the gear 40 in turn meshes with a driving gear 42 on a 40 shaft 43 in mesh with a gear on the shaft of roller 37. The operation of the gearing from the operating rod 20 is effected by means of a universal joint, generally indicated 45, having its rod 46 connected to shaft 20 in the well known customary manner. The web 38 carries suitable inscriptions 45 identical on both of its sides, as for instance as shown in Figure 3 "14th street", and visible through the glass or other transparent 50 windows 47, 48 provided on the casing 13.

The type of device above described is used with the cars illustrated in Figure 1, and if the indicating devices of a number of cars of a train are to be operated from a 55 single handle 33, the shafts 24 are extended lengthwise of the cars and suspended from the car bottoms by means of brackets 21 from which sleeves 49 are suspended, one of which is split, as at 50, and a clip joint 51 60 of pin and slot construction permits coupling of the ends of the shafts 24 within the split sleeve when the cars are coupled, automatically or otherwise. It is to be noted that the elements 49 each include universal 65 joint connections, thus permitting coupling

irrespective of minor lateral or horizontal inequalities of adjacent cars.

In the type of cars illustrated in Figure 2, the posts 31 are erected in the car vestibules and the indicator 13 is operated from the 70 operating handle on post 31 in the above described manner by means of rods 24 and the gears 22 and 23.

The operation of the device will be clear from the above description without further 75 details.

In the form illustrated in Figures 7 and 8 the indicator is automatically operated when the train is leaving a station to automatically indicate the name of the next following station or stop of the train.

As shown in Figure 7, the bracket 21 has a lower extension sleeve 52 through which the lower end of post 30 is extended and carries a substantially triangular plate 53 85 adapted to come into contact with a finger 54 made from resilient material preferably rubber, and attached to the lower part of a bracket 55, secured in a chamber 56 provided in the lower part of the station 90 platform 57. It will be clear that the finger 54 must project for about six inches beyond the end of the platform into the path of the plate 53. Suitable devices may be provided to prevent a turning of the indicator for more than one step at each operation.

It will be clear that with this form of my device all connecting switches will be dispensed with, as the finger on the platform 100 operates in succession, each indicator of the successive order of cars. In cases where the location of the platforms alternate from right to left or vice versa, such fingers must be arranged at both sides of the cars to engage the respective station platform fingers.

It will be clear that changes may be made in the general arrangement and construction of the minor details of my invention without departing from the spirit of the same within the scope of the claims hereto appended.

Having thus described my invention, what I claim as new and desire to secure by Letters Patent, is:-

1. A street and station indicator comprising a means for successively displaying the street and station names in their consecutive order, a frame for supporting said indicator, operating rods in the posts of said frame, a universal joint adapted to be operated from said rods to operate said display means, bevel gears at the lower ends of said rods, shafts extending lengthwise of the cars, bevel gears on said shafts in mesh with said first named bevel gears, stub shafts at an angle to said first named shafts, and means for manually rotating said last named bevel gears to operate said op- 125 130

erating rods from a predetermined point of a car.

2. In a street and station indicator, a frame, a plurality of posts composing said frame, a plurality of operating rods in said posts, means for operating said operating rods from a predetermined point of a car, longitudinally extending operating rods suspended from the car bottom adapted to

be operated from said means, a split sleeve 10 on one pair of longitudinally extending rods, and a pin and slot connection therein adapted to couple the ends of the operating rods on two adjoining cars upon the coupling of the same during the making up of a train. 15

In witness whereof I have affixed my signature.

GEORGE A. KARG.
